PRESS SYSTEM

Thomas F. Stacy, Piqua, Ohio, assignor to The
French Oil Mill Machinery Co., Piqua, Ohio

Application July 28, 1931, Serial No. 553,549

27 Claims. (Cl. 60—52)

This invention relates to hydraulic press systems, and particularly to the control of the main and pull-back rams.

An object of this invention is to improve the construction and operation of such systems.

Another object of the invention is to provide an improved press system with which vibration of the controls will be prevented; with which heating of the pump and operating fluid will be reduced to a minimum; with which the speed of operation of the press will be increased; with which the maximum, desired pressure in the main ram may be maintained automatically for a desired interval of time and the press then opened automatically; and which will be relatively simple, compact and inexpensive.

A further object of the invention is to provide an improved system with which fully or partially automatic and continuous operation of the rams may be obtained selectively; with which the pressure stroke of the platen may be stopped and a return movement started quickly at any point in the pressure stroke of the platen; with which the platen will be held in its returned position under pressure without heating of the continuously operating pump; with which the pressure stroke of the platen may be initiated under manual control, and after the resistance has reached a desired maximum pressure, the return movement of the platen automatically initiated a predetermined interval thereafter; and with which said platen may be caused to travel alternately in opposite directions continuously.

Various other objects and advantages will be apparent from the following description of an embodiment of the invention, and the novel features will be particularly pointed out hereinafter in connection with the appended claims.

In the accompanying drawings:

Fig. 1 is a schematic diagram illustrating one embodiment of the improved system;

Fig. 2 is a side elevation of the automatic control therefor, with the air chest cap removed;

Fig. 3 is a plan of the same;

Fig. 4 is a sectional elevation of the same, the section being taken approximately along the line 4—4 of Fig. 3.

Fig. 5 is a sectional elevation of the same, with the section taken approximately along the line 5—5 of Fig. 3; and

Fig. 6 is a diagram of part of the system showing the changes necessary when a uni-directional pump is substituted for a reversible pump.

In the illustrated embodiment of the invention, referring to Fig. 1, the system, includes a

hydraulic press of any suitable or usual construction, including a platen 10 which moves toward and from a fixed platen, not shown, under the action of the main ram 11 and a pull-back ram 12. The cylinder of the main ram 11 is connected by a pipe 13 to one end of the chamber 14 of a differential valve housing 15, and a similar but smaller pipe 16 connects the cylinder of the pull-back ram 12 to the other end of the chamber 14. A pipe 17 connects an intermediate or central part of the chamber 14 with a source 18 of fluid under pressure. In this instance this course may comprise a tank having an air chamber in its upper end, in which air is compressed so as to exert a yielding pressure on the liquid in the lower part of the tank. The use of such a tank as a source of fluid under pressure is disclosed in my prior U. S. Patent 1,765,627.

A valve ring or seat 19 is disposed across the chamber 14 between the connection thereto of the pipes 13 and 17, and a similar valve seat or ring 20 is disposed across the chamber 14 between the connections thereto of pipes 16 and 17. The opening in the valve seat 19 is larger than that of the seat 20, and is normally closed by the valve element 21 having a stem or tail part 22 slidably mounted in a socket or cavity in the adjacent end of the chamber 14.

A helical compression spring 23 is disposed in the chamber 14 and acts upon the valve element 21 so as to urge this valve element 21 yieldingly against its seat 19. The guiding tail or part 22 of the valve element 21 may be made tubular or hollow to receive the spring 23. A valve element 24 is disposed in the other end of the chamber 14 for cooperation with the seat 20, and includes an operating stem 25 which extends through a wall of the housing 15 into an air cylinder or chamber 26 where it carries an operating piston 27.

The two valve elements 21 and 24 therefore control communication between the pipe 17 and the pipes 13 and 16, these valve elements moving away from one another to permit fluid flow from the pipe 17 toward both of said rams, and automatically closing to prevent return flow into the pipe 17 from the rams. In this respect the valve elements function as two separate free check valves, but one of the valve elements, such as the element 24, is provided with a stem 28 which engages with the element 21 and pushes it into open position when the element 24 is pushed into closed position. By reason of this stem 28, simultaneous seating of both of those valve elements is automatically prevented, yet either element may seat freely when the other element is in open

position, and both valves may be open at the same time.

A pump 29, which may be of the reversible and variable or constant delivery type, is connected at one side by a pipe 30 to the pipe 13 leading to the main ram 11, and this connection may conveniently be obtained by connecting the pipe 30 to the end of chamber 14, in the differential valve housing 15, at the side of the seat 19 where the pipe 13 is connected, so that the pipes 30 and 13 will always be in communication with one another regardless of the position of the valve element 21. Similarly, the other side of the pump 29 may be connected by the pipe 31 to the pipe 16 leading to the cylinder of the pull-back ram, the connection being made through the opposite end of the chamber 14 so that this connection will not be affected by the position of the valve element 24.

20 A free check valve 32 is included in the pipe 31 in such a manner as to open freely and permit fluid flow from the pump through the pipe 31 to the pipe 16, and automatically to close and prevent reverse flow. The pump is therefore so arranged as to deliver fluid under pressure to said rams alternately, and the delivery of fluid from the pump to either of these rams is under the control of a regulating member 33.

30 Reversible, variable delivery pumps of this type are well known in the art and hence it has been shown only diagrammatically, and will not be described in detail.

A branch pipe 34 is connected to the pipe 31 between the pump and the check valve 32, and 35 is connected to a pump bypass valve 35, which also is connected by a pipe 36 to the chamber 14 at a point between the seats 19 and 20. The pipe 36 is in reality directly connected to the pipe 17, leading to the reservoir or source 18 of 40 fluid under pressure. The valve 35 includes a valve element 37 engaging with a valve seat 38 disposed between the connections thereto of the pipes 34 and 36, so as to control communication between the pipes 34 and 36. The valve element 45 37 is provided with a stem 39 which depends outside of the valve housing and is yieldingly urged in a direction to close the valve by a spring 40. The spring 40 normally urges the valve 37 into closed position, and therefore in a sense, the 50 valve is in the nature of a check valve which opens automatically to permit flow from the pipe 36 into the pipe 34, and closes automatically when the flow is in the opposite direction.

55 A rod 41 is guided vertically in a depending arm 42 of the housing of the valve 35, and at its lower end is guided for reciprocation in a bearing 43 extending laterally from the platen 10. The endwise movement of the rod 41 is limited by the engagement of a head 44 of the rod on its upper end with the support 42. When the head 44 of the rod 41 rests upon the depending support 42, the spring 40 will close the valve element 37. The rod 41 is provided with a collar 45 which is slidable along and adjustably secured to the rod in any suitable manner so that it may be set to be engaged by the bearing 43 of the platen 10 when the platen rises under the action of the pull-back ram.

70 When the bearing 43 of the platen engages the collar 45, the continued upward travel of the platen will cause a lifting of the rod 41, and through it, will force the valve element 37 into its open position. The pump then discharges through the pipes 34 and 36 into the pipe 17 to 75 the source 18, but since the valve element 21

would at that time be open, the flow would actually be from the pipe 36 through the chamber 14 to the pipe 30 and thence to the pump. The pipe 36 may be, and preferably is, connected directly to the tank 18 so that fresh oil or operating liquid will circulate through the pump. The pump then may continue to operate at full capacity but without material pressure, since the fluid will be circulated idly through the pump. The pressure on the fluid in the pull-back ram will tend to cause the fluid to return through the pipe 16 and the pipe 31, but this is prevented by the valve 32. The pull-back ram is thus held in its elevated position.

The regulating member 33 is operated to reverse the pump or to change its delivery between the pipes 30 and 31 in any suitable manner, but preferably in accordance with this invention, the member 33 extends into an air cylinder 46 and carries within the cylinder a piston or head 47. 15 Pipes 48 and 49 lead to the interior of said cylinder 46 at opposite sides of the piston 47 so that when a compressed fluid such as air is admitted to either pipe 48 or 49, such compressed air will force the piston 47 in one direction or another, 20 and thus operate the regulating member 33. A branch 50 connects the pipe 48 with the air cylinder or chamber 26 of the differential valve, at one side of the piston 27 thereof, and a pipe 51 connects the pipe 49 to the air chamber 26 of the 25 differential valve on the other side of the piston 27 from the opening into the pipe 50. The piston 27 will therefore be operated concomitantly with the piston 47.

The control of the compressed air admitted to 30 the pipes 48 and 49 will next be explained, having particular reference to all of the figures of the drawings. Referring first particularly to Fig. 5, the control device for the compressed air therein illustrated includes the valve body 52 40 suitably mounted adjacent the press (Fig. 1). This valve body is provided with an air chamber or chest 53 (Figs. 2 and 5) which is normally closed by a cap 54 secured across an open window 55 (Fig. 2) in any suitable manner, such as by 45 cap screws 56. The wall of the air chest 53, which is opposite the cap 54, is provided with ports 57, 58, 59, and 60 arranged in a row in a direction lengthwise of the chamber or chest 53, as shown clearly in Figs. 2 and 5. A slide valve or control 50 element 61 is disposed in said air chest 53 and is pressed continuously against the wall having the ports by a spring 62 carried by the cap 54, as shown clearly in Fig. 5.

A valve rod 63 extends through a removable 55 plug 64 in the bottom of the valve body, and through a packing element 65 into the air chamber or chest 53, and is removably connected within the chamber to the slide valve or element 61. Thus, by reciprocating the valve rod 63, the valve or element 61 may be reciprocated back and forth in the chamber 53 so as to cover and uncover the ports 58 and 60, alternately. The valve element 61 is provided with a cavity or recess 66 on its face which bears against the ported 65 wall, and this cavity 66 connects the port 59 alternately with the ports 58 and 60, so that whether the valve element is in one position or another, the port 59 will always be connected through the cavity 66 with one, and only one, 70 of the ports 58 or 60.

A suitable source of compressed fluid such as air is connected through a pipe 67 (Fig. 2) and a passage 68 in the valve body, with the port 57, so that the air chest or chamber 53 will always be 75

filled with compressed air. When the valve element 61 is in its lower position, which is shown in Fig. 5, this compressed air will pass through the port 58 into a passage 69 in the valve body to which is connected the pipe 48. The compressed air would therefore pass through the pipes 48 and 50 and cause an operation of the pump regulating member 33 and the differential valve element 24 in a manner to start operation of the pull-back ram to return the platen to the position shown in Fig. 1.

The port 59 is connected by the passage 70 to a pipe 71 which is an exhaust pipe, into which the compressed air or fluid escapes from the pipes 48 and 49. The port 60 is similarly connected by a passage 72 (Figs. 2 and 5) with the pipes 49 and 51. When the control valve or element 61 is shifted upwardly from the position shown by full lines in Fig. 5, it will uncover the port 60, and the cavity 66 will connect the ports 58 and 59. This position of the element 61 is shown by the dotted lines in Fig. 5. The compressed air will then no longer pass through the port 58 to the pipe 48, but instead will pass through the port 60 and passage 72 into pipe 49. The exhaust port 59 will be connected with the port 58, so that any compressed air which previously had been admitted to the pipe 48 could escape to atmosphere. This causes an actuation of the regulating member 33 and of the valve element 24 in the opposite directions, so as to start operation of the main ram 11 and force the platen 10 downwardly.

The valve rod 63, at its lower end, is connected to a yoke 73 and the latter in turn is connected to the lower end of a pair of rods 74 which pass upwardly through bearing passages 75 in the valve body 52, and above the valve body are connected by a yoke 76. The lower ends of the passages 75 are enlarged to form recesses 77 (Fig. 2) which receive helical compression springs 78 surrounding the rods 74 and bearing upon washers 79 held in position on the rods by nuts 80 on the rods 74. The springs 78 urge the rods 74 downwardly, and through the yoke 73 and valve rod 63 urge the slide valve or element 61 downwardly into its lowermost position, shown in full lines in Fig. 5. A latch or lever 81 is pivoted at 82 to the yoke 76. A pair of springs 83 are connected between the lever 81 and suitable studs 84 on the yoke 76 so as to urge the latch lever yieldingly in a counter-clockwise direction in Fig. 5.

The latch or lever 81 has a depending nose 85 which, in the position of the yoke 76 shown in Fig. 5, bears against a side face of an abutment 86 that is provided upon the upper end of the valve body 52. When the yoke 73 is elevated, the springs 78 will be compressed to a greater extent, and the latch or lever 81 will be bodily elevated with yoke 76 until a notch 87 in the lower end of the nose 85 snaps over an upper corner edge of the abutment 86 under the action of the springs 83. If then the yoke 73 is released, the springs 78 would urge the yoke 76 and the latch or lever 81 downwardly, but this downward movement of the yoke 76 will not take place because of the engagement of the latch or lever 81 with the abutment 86. The slide valve or element 61 will thus be held reasonably in its upper position in which it passes compressed air to the pipe 49 to start operation of the main ram.

The pump then delivers fluid, under pressure, through pipes 30 and 13 to the main ram 11, and the platen 10 moved downwardly. As the resistance offered to the platen 10 increases, the pressure of the actuating fluid in the main ram will

increase, and this increased pressure is utilized to disengage the latch 81 a desired interval of time after the maximum desired pressure in the cylinder of the main ram has been reached, as will now be explained.

The valve body 52 is provided with a cylinder or chamber 88 (Fig. 5) which is closed at its lower end by a removable plug 89. A piston 90 reciprocates vertically in the cylinder 88 and is provided with a stem 91 which extends outwardly through a bearing passage in a removable plug 92 which closes the upper end of the chamber 88, a packing gland 93 being provided for the stem 91 before it passes through the plug 92. The outer end of the stem 91 carries an adjustable trip screw 94 which engages a tail 95 of the latch or lever 81, rocking the latter in a clockwise direction in Fig. 5 against the tension of the springs 83 until it disengages the notch 87 from the abutment 86. Thereupon, the springs 78 force the rods 74 downwardly, and thereby shift the slide valve 61 downwardly into the position shown in full lines in Fig. 5. This shifts the delivery of fluid from the pump to the pull-back ram instead of the main ram, and starts a return travel of the platen 10.

The piston 90 telescopes over and slides upon a stud 96 projecting into the chamber or air cylinder 88 from the plug 89, and the stud 96 is provided with a passage 97 extending from end to end. The lower end of stud 96 is connected by a pipe 98 to the cylinder of the main ram 11. The fluid pressure in the main ram 11 is thus transmitted through the pipe 98 and the passage 97 to the underside of the piston 90. The effective pressure area on the piston is the area of the opening or cavity which fits over the stud 96 and is considerably smaller than the maximum diameter of the piston 90.

Secured to the upper and outer end of the piston stem 91 by the trip screw 94 is a yoke 99 (Figs. 3, 4, and 5, and the ends of this yoke are secured to the upper ends of a pair of rods 100 which pass downwardly through the valve body 52 in which they are slidably mounted. The passages in the valve body 52 through which the rods 100 pass are enlarged at their lower ends and form cavities 101 (Fig. 4). Helical springs 102 are compressed between the upper or inner ends of the cavities and washers 103 confined on the rods 100 by nuts 104. The springs 102 thus urge the rods 100 downwardly and thus through the yoke 99 resiliently urge the piston 90 into its lowermost position, shown in Fig. 5.

No appreciable upward movement of the piston 90 will occur until the pressure thereon transmitted through the passage 97 from the main ram is sufficient to overcome or compress the springs 102. When the pressure on the piston 90 builds up sufficiently to overcome the resistance of the springs 102, the fluid displaced in the cylinder 88 by the piston 90 is controlled in its escape in a manner to regulate variably, the rate of travel of the piston 90, and thus delay the tripping of the latch or lever 81 for a desired interval after any selected pre-determined pressure has been built up in the main ram.

A pipe 105 (Fig. 5) leading from any suitable reservoir or source of fluid (not shown) is connected to a passage 106 in the valve body 52, which passage leads to the underside of the enlarged head of the piston 90. A branch passage 107 leads upwardly from the passage 106 into a transversely extending passage 108. A free seating check valve 109 is provided at the junction between the passages 107 and 108 so as to

permit free upward flow of fluid from the passage 107 into the passage 108. Another passage 110 (Fig. 4) extends downwardly from the passage 108 and intermediate its ends is provided 5 with a seat 111. The portion of the passage 110, which is below the seat 111, is somewhat larger than the portion of the passage above the seat. A needle valve stem 112 passes through and is threaded into a plug 113 which closes the 10 lower end of the passage 110, and also passes through a packing gland 114 at the upper end of the plug 113. The tapered tip of the needle valve stem cooperates with the seat 111 to restrict or regulate variably, the fluid flow along 15 the passage 110. A further branch passage 115 connects the lower end of the passage 110 with the passage 106. The upper end of the cylinder 88 (Fig. 5) is connected with the passage 108 by a short passage 116. (Figs. 4 and 5). 20 From the foregoing description it will be observed that any fluid displaced from the upper end of the cylinder 88 by the upwardly moving piston 90 (Fig. 5) will pass through passage 116 into the passage 108, and cannot pass downward- 25 ly through the passage 107 because of the automatic seating of the check valve 109. Consequently this displaced fluid will pass along passage 108 (Fig. 4) and into and through the passage 110 where its flow is regulated by the needle 30 valve, and thence will pass through passage 115 into the passage 106, from which a part of it may enter the space in the cylinder 88 below the piston head 90 and the remainder may pass through the pipe 105 to the source or reservoir 35 (not shown). By suitably adjusting the needle valve stem 112 through manipulation of its head 116, the escape of the displaced fluid from the cylinder 88 is regulated, and hence the travel of the piston 90 may be regulated to occupy any 40 desired interval of time after the pressure in the main ram has equaled or exceeded a desired pressure corresponding to that necessary to overcome the springs 102. The control of the pump may be set so that when any desired 45 maximum pressure has been reached, the pump will come toward neutral and will maintain this pressure. Such pumps are articles of commerce and, per se, are not part of this invention. The regulation of the time interval through adjustment of the needle valve stem 112 enables one to regulate the time from zero to any desired period during which the pump is holding this desired pressure. In other words, with this combination it is possible to have a time dwell on 50 the press under pressure and the pressure and the time are both adjustable.

When the latch 81 is tripped at the completion of the upward travel of the piston 90, the operation of the platen 10 is reversed and the pull-back ram is made effective. The pressure in the main ram thereupon falls very materially and quickly, whereupon the springs 102 will return the piston 90 to its lowermost position. During this descent of this piston 90, the fluid 55 displaced by its head from the lower part of the chamber or cylinder 88 will escape through passage 106 and pass either directly to the reservoir through passage 105, or will move upwardly in passage 107, lift the check valve 109, and then 60 move through passages 108 and 116 into the upper end of the cylinder 88, so as to occupy the increasing space in the upper end of the cylinder 88 caused by the descent of the piston head. Since the fluid displaced beneath the piston head 65 75 will be less than that displaced above the pis-

ton head, the fluid which is displaced from beneath the head will all travel upwardly in the passage 107, and some of the fluid which was displaced to the reservoir through pipe 105 when the piston 90 was ascending, will return through pipe 105 and passages 106, 107, 108, and 116 to the upper end of the cylinder 88. 5

If the yoke 76 has been elevated and latched in elevated position by the latch 81, the main ram 11 is effective to cause the descent of the 10 platen 10. The descent of the platen 10 is not stopped until the latch 81 is released by the upward movement of the piston 90 after a desired minimum pressure has been built up in the main ram and maintained therein for a selected interval of time. It may happen that one may desire to check the descent of the platen before a complete cycle has been completed, as a safety feature, and for this purpose a safety release member 117 is slidably mounted for vertical 15 movement in any suitable manner, such as shown in Fig. 2, on the yoke 76, and is provided with a slot 118 extending vertically and into which extends another tail 119 of the latch or lever 81. 20

An operating rod 120 depends from the member 117 and is guided vertically in a suitable bearing 120a (Fig. 1) on the base of the press and an arm 121 of the platen. A spring 122 on the rod 120 acts between a collar 123 on the rod and the bearing 120a to elevate the rod 120 25 and hold it in its upper position shown in Figs. 1 and 5. When the member 117 is in this elevated position, as shown in Figs. 1 and 5, the yoke 76 may move upwardly or downwardly in order to cause the engagement of the latch 81 30 with the abutment 86 or the descent of the yoke after the latch is disengaged from the abutment, and during such movement the tail 119 of the latch 81 moves idly in the slot 118 of the release member 117. 35

Assuming that the latch has been elevated with the yoke and engaged with the abutment 86, the tail 119 will then be nearer the upper end of the slot 118. If then the release member 117 is moved downwardly by a downward pull 40 on the rod 120, the upper end of the slot 118 will engage the tail 119 and rock the latch or lever 81 clockwise in Fig. 5 and disengage it from the abutment 86. This causes a movement of the slide valve or element 61 and through 45 it a stopping and reversing of the direction of travel of the platen 10 before the platen has completed its full downward stroke. The lower end of the rod 120 may be connected to a suitable 50 operating lever 124 having a handle disposed in a position convenient for operation by the press operator. 55

Since a downward travel of the platen 10 is initiated by an upward movement of the slide valve or element 61, suitable means has been 60 provided for causing this movement of the slide valve. A rod 125 (Fig. 1) is suitably guided in the bearing 121 of the platen and in other bearings 126 on the frame of the press, and this rod 125 at its upper end (Figs. 1 and 2) is disposed just below the yoke 73 which is connected to the lower end of the valve operating rod 63. A spring 127 acts between one of the bearings 126 and a shoulder on the rod 125 so as to yieldingly hold the rod in its lower position which is 65 determined by a stop pin 128 in the path of a lever or foot pedal 129 and which engages and operates the lower end of the rod 125, as shown in Fig. 1. The pedal or lever 129 is pivoted at 70 130 so that when the free end of the lever is 75

displaced, the rod 125 will be elevated into engagement with the yoke 73 and further movement will cause an upward movement of the yoke and the slide valve 61. This starts a downward movement of the platen 10.

According to this arrangement, a downward movement of the platen is initiated by manual operation of the trip pedal 129, but in some instances it may be desirable to have full automatic operation or a continuous up and down movement of the platen. Accordingly, I provide a collar 131, (Fig. 1) upon the rod 125 in a position to be engaged by the bearing 121 on the platen 10, when the platen reaches approximately its upper limit of movement. The final upward movement of the platen thus elevates the rod 125 automatically and through it shifts the valve 61 to start a new downward movement of the platen. The collar 131 is secured in different adjusted positions along the rod 125 in any suitable manner, such as by a set screw 132, so that the collar may be set to stop upward movement and start a downward movement at different points in the upward movement of the platen 10.

If desired, the collar 131 may be shifted or adjusted upwardly beyond the reach of the platen 10, so that the platen 10 will be stopped in its upward travel by its engagement with collar 45 before it can operate the slide valve and initiate a downward movement of the platen. It will be understood that when the collar 131 is adjusted into a position to cause a full automatic operation of the platen 10, the collar 45 may be adjusted into a position into which it is not engaged by the platen since the purpose of the pump by-pass valve 35 is to stop the upward travel of the platen and to hold the platen in that stopped or elevated position.

The rod 41 (Fig. 1) may be connected to the stem 39 of the pump by-pass valve element 31, or it may merely engage the same endwise, but if directly attached to it, it is preferable to provide a second free check valve 133 in a branch pipe 134 connecting the pipes 34 and 36. This check valve 133 opens freely to permit flow from the pipe 36 into the pipe 34 and automatically seats to prevent reverse flow.

The operation of this system should be obvious from the foregoing description of the construction, but will be briefly summarized. Assuming first that the platen is at its upper limit of movement as shown in Fig. 1, and that the collar 131 is positioned as shown in Fig. 1, so as not to be elevated by the platen when the platen reaches its upper position, thus making the press set for semiautomatic operation. To initiate an operation of the press, the operator depresses the pedal 129 which causes an elevation of the rod 125 and through it an elevation of the slide valve 61. Thereupon the compressed air from the chest 53 (Fig. 5) would pass through the port 60, passage 72 and pipe 49 to the air cylinder 46, and also pass through the branch pipe 51 to the air cylinder 26 of the differential check valve. This causes an operation of the piston 47 of the air cylinder 46 to the right in Fig. 1, so as to cause the pump 29 to deliver fluid under pressure to the pipe 30 and get its suction from the pipes 31 and 34.

At the same time the differential check valve stem 25 is elevated by the piston 27, thus lifting valve element 24 and opening communication between the reservoir pipe 17 and the pipe 16 leading to the pull-back ram 12. The

fluid in the pull-back ram is then allowed to escape through the seat 20 into the central part of the chamber 14 where it may pass either into the pipe 17 or through the pipe 36 and either or both of the check valves 35 and 133 into the pipe 34 leading to the intake side of the pump. The fluid or liquid in tank 18 is stored under pressure, which may be either pneumatic pressure, or an accumulator, or the pressure may be created in any other manner. At this time the pressure in the main ram 11 is very small, because it has previously been connected to the intake side of the pump. Immediately at the beginning of the operation of the main ram, the fluid from the tank 18 which has a pressure higher than that of the main ram will force open the check valve or element 21, move rapidly into the main ram, and force the platen 10 downwardly at a rapid rate until the platen meets considerable resistance.

When this resistance approximately balances the pressure created by the fluid from the tank 18, the check valve element 21 will close under the action of the spring 23, this closing being permitted since the other check valve element 24 is open. The fluid delivered by the pump through the pipe 30 and pipe 13 to the main ram then builds up the pressure in the main ram to the maximum desired. The pressure in the main ram 11 is transmitted through pipe 98 to the passage 97 in the stud 96 (Fig. 5) and when the pressure on the piston 90 within the cavity which slides over the stud 96 is sufficient to overcome the resistance of the springs 102, the piston 90 will travel upwardly at a rate controlled by the regulation by the needle valve stem 112, and after an interval which is pre-determined by the regulation of the needle valve stem, the strip screw 94 will engage and rock the latch 81 into disengaged position, whereupon the springs 78 will cause the yoke 73 to descend and lower the slide valve 61 into the position shown in full lines in Fig. 5.

The port 60 is then connected to the exhaust port 59 so as to release the pressure in the pipes 49 and 51 (Fig. 1) and at the same time the compressed air from the chest 53 (Fig. 5) will pass through port 58, passage 69 (Figs. 2 and 5), the pipe 48 (Figs. 1 and 2) to the opposite side of the air cylinder 46, to cause a reverse travel of the piston 47 and a reversal of the delivery of the pump. At the time air from the pipe 48 (Fig. 1) moves through the branch 50 to the cylinder on the differential check valve, and forces the valve element 24 promptly into closed position on the seat 20, and in doing so the stem 28 engages and opens the check valve element 21.

The pump then delivers fluid under pressure into the pipes 31 and 34, but the check valves 35 and 133 automatically prevent movement of the fluid through pipe 34, and hence the fluid travels entirely through the pipe 31 and check valve 32 into the pipe 16 and thence to the pull-back ram 12. The platen then starts its upward travel. At the instant that the pump is reversed, the valve element 21 is opened as explained, and the high pressure in the main ram 11 is at once relieved, allowing return of the piston 90 (Fig. 5) into its lowermost position under the action of the springs 102. The main ram has a greater displacement than the pull-back ram, and the fluid from the main ram passes through the differential check valve and

the pipe 17 into the storage tank or reservoir 18 where the pressure is again built up to the desired extent.

Some of the fluid displaced by the main ram 5 of course passes through the pipe 30 to the intake side of the pump for delivery to the pull-back ram. This operation continues until the platen 10 engages the collar 45 at its upper limit of movement, and elevates the rod 41 thus opening 10 the check valve 35. This short circuits the delivery of the pump away from the pull-back ram and directly back to the source 18 or to the pipe 30, since the valve element 21 remains open because of the engagement of the stem 28 therewith. The pump thus may continue to operate at full capacity, but the fluid is circulated idly through the pipes 34, 36, and 30, so that there will be no heating of the pump since there is practically no load upon it. The pressure built 15 up in the pull-back ram 12 is maintained, because the check valve 32 prevents return flow, and thus the platen 10 will remain in this position until a new operation is initiated by operation of the lever 129.

25 Suppose, that full automatic operation of the press now is desired. The operator will move the collar 131 along the rod 125 and secure it thereto in a position to be engaged by the bearing 121 at the same time that the collar 45 is 30 engaged by the bearing 43 of the platen, or at the desired upper limit of movement of the platen. With that setting of collar 131, when the platen 10 reaches its desired upper position it engages the collar 131 and elevates the 35 rod 125 to start a new downward movement in the same manner that operation of the lever 129 at that instant would have done. The platen 10 then starts on a new power stroke, and will 40 continue to move upwardly and downwardly automatically in this cycle until the operator shifts the collar 131 out of the range of operation of the platen 10.

In the embodiment of the invention illustrated in Fig. 6, a uni-directional delivery pump 45 135 is shown as substituted for the reversible pump 29 of Figs. 1 to 5. Changes in the system arising from the substitution of the uni-directional pump are shown in this figure, the remainder of this system being the same as in 50 Figs. 1 to 5. The intake side of the pump 135, which always operates continuously in the same direction, is connected by pipe 136 to the source of fluid under pressure which in this embodiment of the invention may be to the pipe 17. The 55 output side of the pump 135 is connected by a pipe 137 to a port 138 in a valve housing 139. A valve element 140 is reciprocated in the housing 139 by regulating member 33 and connects the port 138 alternately with the pipes 30 and 60 31 of Fig. 1. The valve element 140 when reciprocated by the regulating member 33 therefore delivers the output of the pump to either the pipe 30 or 31 in accordance with the position of the regulating member 33.

65 In Figs. 1 to 5, the operating medium for the pistons 47 and 27 was mentioned as compressed air by way of example, and it is a simple and inexpensive medium for the purpose. However, it is possible and sometimes desirable to operate the 70 system without the use of compressed air, and one example of the changes which will accomplish this result is shown also in Fig. 6. For this purpose a choke 141 is placed in the pipe 137 so as to insure that the pump will always operate 75 under a selected minimum pressure, such as

one hundred pounds per square inch or over. Such chokes are well known in the art and may be of the sliding type, or may be a check valve 5 spring-pressed toward its seat to resist the flow of fluid through the pipe 137 until the pressure equals or exceeds that necessary to lift the valve from its seat against the action of its spring, which is said selected minimum pressure. The pipe 67, which supplies the compressed fluid to the control device, is then connected to the pipe 10 137 between the pump 135 and the choke 141, and hence the liquid or other fluid being handled by the pump will be supplied, under a pressure equal to or exceeding said minimum, to the air chest or chamber 53. While only a small amount of this fluid would actually pass out through the exhaust 59 if the exhaust were open, any loss of such fluid may be prevented by connecting the exhaust pipe 71 to the pipe 17. With this system otherwise arranged as explained in 20 Figs. 1 to 5, the operation is the same.

The pump and operating fluid will not heat while the pull-back ram is holding the platen in its elevated position because the pump is operating idly. The operation of the press under 25 this system is very rapid, and free from undesirable vibrations. While compressed air or other fluid has been described as the actuating medium of the controlling mechanism, it will be understood that other equivalent means may 30 be substituted if desired.

It will be understood that by adjusting the tension of the springs 102, which resist the upward movement of the trip piston 90 and stem 91, one may vary the pressure which must be 35 reached in the main ram before the timing action starts. Consequently, the pressure in the main ram at which the springs 102 are overcome is the pressure which must be reached in the main ram before the timing device begins to operate, and this pressure may also be nearly the maximum pressure when a pump is used of the type which builds up the pressure in the main ram to a desired extent and then holds the pressure unchanged. Where the ordinary pump is 45 used, the timing device begins to operate after the selected pressure has been reached in the main ram, and while the timing device is operating the pressure in the main ram and on the timing piston 90 is increasing above the selected 50 pressure at which movement of the timing piston was initiated.

It will be obvious that various changes in the details, which have been herein described and illustrated in order to explain the nature of the 55 invention, may be made by those skilled in the art within the principle and scope of the invention as expressed in the appended claims.

I claim:

1. In a hydraulic press system, a platen, a main ram and a pull-back ram connected to said platen for operating it alternately in opposite directions, a source of operating fluid, means including a pump connected to said rams for delivering fluid from said source to each of said 65 rams and from each ram to the other alternately in accordance with the desired direction of operation of said platen, a freely opening check valve in the connection from said pump to said 70 pull-back ram separate from the connection from the pump to the main ram permitting free flow of fluid from the pump to the pull-back ram and automatically preventing reverse flow, by-pass valve means connecting said source to the connection between said pump and said check valve, 75

- and operable to by-pass to said source the fluid delivered by said pump and intended for said pull-back ram, and a free check valve shunting said by-pass valve means and opening freely 5 to pass fluid toward said pump, whereby the action of the pull-back ram may be stopped and the platen held in any desired position during the return movement of said platen.
2. In a hydraulic press system, a platen, a main 10 ram and a pull-back ram connected to said platen for operating it alternately in opposite directions, a source of operating fluid, means including a pump connected to said rams for delivering fluid from said source to each of said rams and 15 from each ram to the other alternately in accordance with the desired direction of operation of said platen, a check valve in the connection from said pump to said pull-back ram separate from the connection from the pump to the main 20 ram, permitting free flow of fluid from the pump to the pull-back ram and automatically preventing reverse flow, a by-pass valve connecting said source to the connection between said pump and said check valve, and operable by said platen 25 when said platen reaches a desired point in its return movement for stopping the delivery of fluid from the pump to the pull-back ram, whereby the action of said pull-back ram will be stopped and said platen held in the position in which it 30 stops, automatically, and a free check valve shunting said by-pass valve and yielding to flow solely in a direction toward said pump and oppositely from the flow through said by-pass valve when the latter is opened by said platen.
3. In a press system, a platen, a pull-back ram and a main ram connected to said platen and operating it in alternate directions, a source of fluid, a variable delivery, reversible pump, pipes to said rams from said pump for delivering 40 fluid from said source to said rams alternately, a branch pipe from said pump, at the side connected to the pull back ram, to said source, a valve solely in the pipe from said pump to said source and operable automatically when the 45 platen reaches a desired point in its return movement for diverting fluid from said pump to said source, a free check valve by-passing said automatically operable valve in the pipe from said pump to said source, and opening automatically 50 to pass fluid from said source to said pump and opposing reverse flow, and means for changing the delivery of said pump from the pull-back ram to the main ram to start a new power stroke with said main ram.
4. In a press system, a platen, a pull-back ram and a main ram connected to said platen and operating it in alternate directions, a source of fluid, a single, high pressure pump for delivering fluid from said source to said rams alternately, 60 a valve operable automatically when the platen reaches a desired point in its return movement for diverting fluid from said pump to said source, means for changing the delivery of said pump from the pull-back ram to the main ram to start 65 a new power stroke with said main ram, and means operable by the pressure of fluid from said pump, normally inactive, but made active automatically a predetermined length of time after the pressure on said main ram reaches a desired 70 predetermined pressure for changing the delivery of fluid by the pump to the pull-back ram instead of the main ram to start the return movement of the platen.
5. In a press system, a platen, a pull-back ram 75 and a main ram connected to said platen for op-
- erating it in alternate directions, a source of fluid, a pump for delivering fluid from said source to said rams alternately, means for changing the delivery of fluid from said pump to said rams so as to operate either ram selectively, a relatively low pressure, fluid actuated, control device for controlling said last named means and having a controlling valve device operated by the relatively high fluid pressure in said main ram to change delivery of fluid from said pump to said pull-back ram instead of the main ram automatically a predetermined and selected length of time after the pressure in the main ram has reached a desired pressure. 5
6. In a hydraulic press system, a platen, a main 10 ram and a pull-back ram connected to said platen for operating it in alternate directions, a source of fluid, a pump connected to said source and to each of said rams for delivering fluid under pressure to each of said rams alternately, means for causing said pump to deliver fluid selectively to either of said rams, and a relatively low pressure regulatable dash pot timing device operable on said last named means and controlled by the relatively high pressure in the main ram to cause the 15 pump to deliver its fluid to the pull-back ram automatically after the pressure in said main ram reaches a desired pressure. 20
7. In a hydraulic press system, a platen, a main 25 ram and a pull-back ram connected to said platen for operating it in alternate directions, a source of fluid, a pump connected to said source and to each of said rams for delivering fluid under pressure to each of said rams alternately, means for causing said pump to deliver fluid selectively to either of said rams, and an adjustable timing device operable on said last named means and normally inactive but set into operation automatically where the pressure in the main ram exceeds a predetermined desired pressure to cause 30 the pump to deliver its fluid to the pull-back ram automatically a pre-determined selected and adjustable interval after the pressure in said main ram reaches said desired pressure. 35
8. In a hydraulic press system, a platen, a main 40 ram and a pull-back ram connected to said platen for operating it in alternate directions, a source of fluid under pressure, means for transferring fluid between said rams alternately, a source of operating fluid, pipe means leading from said 45 source to each ram, said pipe means, said transferring means, said source and said rams together forming a hydraulic system, a valve in the pipe means to each ram, each valve having an individual, movable valve element, said elements being so formed and interacting that when either element is closed, it automatically prevents closing of the other element and each element can open independently of the other, and means 50 separate from said transferring means extending exteriorly of the hydraulic system and operable upon one of said valve elements for shifting it into and out of closed position. 55
9. In a hydraulic press system, a platen, a main 55 ram and a pull-back ram connected to said platen for operating it in alternate directions, a source of fluid, a valve housing having a chamber, a connection from said chamber to said source, a connection from each ram to different parts of said chamber, a separate valve controlling each connection from a ram to said chamber, said valves being disposed and constructed to engage one another and prevent the simultaneous seating of both, and moving away from one another in an opening direction so that both may be open at 70
- 75

- the same time, a pump for transferring fluid between said rams alternately, means separate from said pump for causing said pump to deliver to either ram selectively and having a member positively operable directly upon the valve controlling the connection from the pull back ram to said chamber, whereby the valve in the connection to the pull-back ram will be forcibly opened immediately when the pump delivers fluid to said main ram and will be forcibly closed to open the other valve in the connection to the main ram, whenever said pump is caused to deliver fluid to the pull-back ram.
10. In a hydraulic press system, a platen, a main ram and a pull-back ram connected to said platen and operating it in alternate directions, means for delivering fluid under pressure to said rams alternately, means for controlling the delivery of fluid to each of said rams including a control element yieldingly urged into one position in which the pull-back ram is made effective and operable against such urging into a position in which the main ram is made effective, a latch for holding said element releasably in said last named position, a cylinder having a connection to said main ram, a piston in said cylinder operable by pressure in said main ram, a valve controlling escape of fluid displaced by said piston so as to regulate the rate of movement of said piston under the pressure of said main ram, and means yieldingly urging said piston against the pressure of said main ram, whereby said piston will be operated only when the pressure in said main ram exceeds a pre-determined pressure, said piston having a part operable upon said latch to release said element a pre-determined interval after the pressure in said main ram has reached said pre-determined pressure.
11. In a hydraulic press system, a platen, a main ram and a pull-back ram connected to said platen for operating it alternately in opposite directions, a source of fluid connected to both of said rams, a valve in the connection to each ram, a reversible pump connected to both of said rams for transferring fluid between them alternately, means by which simultaneous closing of said valves is prevented, a check valve in the connection from said pump to said pull-back ram, opening freely for the flow from said pump to said pull-back ram and automatically closing to prevent return flow toward said pump, and a connection from said pump at its output side, when delivering to said pull-back ram, to said source and having a check valve therein seating automatically under the pressure from said pump when said pump is delivering toward said pull-back ram, and opening automatically when said pump is delivering to said main ram.
12. In a hydraulic press system, a platen, a main ram and a pull-back ram connected to said platen for operating it alternately in opposite directions, a source of fluid connected to both of said rams, a valve in the connection to each ram, a reversible pump connected to both of said rams for transferring fluid between them alternately, means by which simultaneous closing of said valves is prevented, a check valve in the connection from said pump to said pull-back ram, opening freely for the flow from said pump to said pull-back ram and automatically closing to prevent return flow toward said pump, a connection from said pump at its output side, when delivering to said pull-back ram, to said source and having a check valve therein seating automatically under the pressure from said pump when said pump is

delivering toward said pull-back ram, and opening automatically when said pump is delivering to said main ram, and means operable by said platen when said platen reaches a desired point in its return movement under the action of the pull-back ram for opening forcibly said second check valve to permit delivery of fluid from said pump directly to said source. 5

13. In a hydraulic press system, a platen, a main ram and a pull-back ram connected to said platen for operating it alternately in opposite directions, a source of fluid connected to both of said rams, a valve in the connection to each ram, a reversible pump connected to both of said rams for transferring fluid between them alternately, 10 means by which simultaneous closing of said valves is prevented, a check valve in the connection from said pump to said pull-back ram, opening freely for the flow from said pump to said pull-back ram and automatically closing to prevent return flow toward said pump, a connection from said pump at its output side, when delivering to said pull-back ram, to said source, a valve in said connection from said pump to said source and operable by said platen into open position when 15 said platen reaches a desired point in its return movement under the action of the pull-back ram, whereby the by-passing of the fluid from said pump to said source instead of the pull-back ram, stops the operation of said pull-back ram, and a free check valve connected in parallel to said 20 platen operated valve and opening freely under flow of fluid from said source to said pump, and automatically seating to prevent return flow. 25

14. In a press system, a platen, a pull-back ram 35 and a main ram connected to said platen for operating it in alternate directions, a source of fluid, a pump, connections from said pump to said rams for delivering fluid from said source to said rams alternately, means for changing the delivery of 40 fluid from said pump to said rams so as to operate either ram selectively, a pressure opened choke in the connections from the output side of said pump to said rams to cause said pump to operate at all times under a pressure above a 45 selected minimum, and opening to pass fluid freely whenever the pressure of fluid delivered by said pump exceeds said minimum, and means connected to the output side of said pump between said pump and said choke and controlled by the 50 platen at a desired point in its return movement for changing the delivery of said pump from the pull-back ram to the main ram to start a new power stroke of the main ram.

15. In a press system, a platen, a pull-back ram 55 and a main ram connected to said platen for operating it in alternate directions, a source of fluid, a pump, connections from said pump to said rams for delivering fluid from said source to said rams alternately, means for changing the delivery of 60 fluid from said pump to said rams so as to operate either ram selectively, a pressure opened choke in the connection from the output side of said pump to said rams to cause said pump to operate at all times under a pressure above a selected 65 minimum, and opening to pass fluid freely whenever the pressure of fluid delivered by said pump exceeds said minimum, and means connected to the output side of said pump between said pump and said choke and controlled by the pressure in 70 said main ram for changing the delivery of said pump to said pull-back ram after a desired pressure has been created in the main ram.

16. In a press system, a platen, a pull-back ram and a main ram connected to said platen for op- 75

- erating it in alternate directions, a source of fluid, a pump, connections from said pump to said rams for delivering fluid from said source to said rams alternately, means for changing the delivery of 5 fluid from said pump to said rams so as to operate either ram selectively, a pressure opened choke in the connections from the output side of said pump to said rams to cause said pump to operate at all times under a pressure above a selected minimum, 10 and opening to pass fluid freely whenever the pressure of fluid delivered by said pump exceeds said minimum, means connected to the output side of said pump between said pump and said choke and controlled by the platen at a desired point in its 15 return movement, and by the pressure in the main ram after a desired pressure has been created in the main ram, for changing the delivery of fluid from one ram to the other and thereby maintain continuous reciprocatory movement of said platen. 20
17. In a hydraulic press system, a platen, a main ram and a pull-back ram connected to said platen for operating it in alternate directions, a source of fluid under pressure, means including a pump and selectively operable for transferring fluid between said rams alternately, a valve device having a chamber connected to said source and to each of said rams, said valve having separate valve elements, one controlling flow in the connection from said source to one ram and the other controlling 25 flow in the connection to the other ram, said valve elements having interengaging parts by which simultaneous closing by both valves is prevented, means for reversing the delivery of said transferring means from one ram to the other, 30 and means operable by said reversing means from the exterior of the valve chamber for forcibly opening one of the valve elements when the pump delivers fluid to said main ram, and forcibly closing said one of said valve elements when said pump 35 delivers fluid to said pull-back ram. 40
18. In a hydraulic press system, a platen, a main ram and a pull-back ram connected to said platen for operating it in alternate directions, a source of fluid under pressure, a connection from 45 said source to each of said rams, a valve in the connection to each ram and having a movable valve element controlling fluid flow in that connection, said valve elements having parts interengaging one another by which simultaneous closing 50 of both valve elements is prevented, a piston connected to the valve element of that valve which is in the connection to the pull-back ram for forcibly operating that valve element in both directions, fluid pressure actuated means for operating 55 said piston selectively in either direction, a pump for transferring liquid from one ram to the other in either direction selectively, fluid actuated means for changing the delivery of said pump from one ram to another, and a common controlling means for both of said fluid actuated 60 means. 65
19. In a hydraulic press system, a platen, a main ram and a pull-back ram connected to said platen for operating it in alternate directions, a source of fluid under pressure, a connection from 70 said source to each of said rams, a separate check valve in the connection to each ram and having a movable valve element opening for flow from said source to the ram and automatically closing to prevent reverse flow, the valve elements of said check valves having interengaging parts by which simultaneous closing of both valve elements is prevented, a piston connected to the valve element of that check valve which is in the connection to the pull-back ram for 75
- forcibly operating that check valve in both directions, fluid pressure actuated means for operating said piston selectively in either direction, a pump for transferring liquid from one ram to the other in either direction selectively, fluid actuated means for changing the delivery of said pump from one ram to another, a controlling device for regulating the movement of actuating fluid to said piston and to said pump delivery changing means, manual means for controlling 10 said controlling device, and means operated automatically by the platen for also controlling said controlling device in accordance with the movements of the platen. 15
20. In a hydraulic press system, a platen, a main ram and a pull-back ram connected to said platen for operating it in alternate directions, a source of fluid under pressure, a connection from 20 said source to each of said rams, a separate check valve in the connection to each ram and having a movable valve element opening for flow from said source to the ram and automatically closing to prevent reverse flow, the valve elements of said check valves having interengaging parts by which simultaneous closing of both valve elements is prevented, a pilot cylinder having a piston reciprocating therein and connected to the valve element of that check valve which is in the connection to said pull-back ram, connections for admitting a fluid under 25 pressure selectively to opposite sides of said piston for causing movement of said piston in a desired direction, a pump connected to said rams for transferring fluid from one ram to another in either direction selectively, a device for regulating the delivery of said pump in order to change the delivery from one ram to the other, an operating cylinder having a reciprocating piston therein connected to said regulating device for operating the latter, connections to said 30 operating cylinder on opposite sides of its piston for causing selected actuation of that piston, a controlling device to which the connections from said operating cylinder and said pilot cylinder lead, whereby the pistons in both of these 35 cylinders will be operated concomitantly in a direction determined by said control device, and manually operated means for operating said control device to admit fluid to said pilot and operating cylinders in a manner to cause a 40 downward movement to said platen. 45
21. In a hydraulic press system, a platen, a main ram and a pull-back ram connected to said platen for operating it in alternate directions, a source of fluid under pressure, a connection from 50 said source to each of said rams, a separate check valve in the connection to each ram and having a movable valve element opening for flow from said source to the ram and automatically closing to prevent reverse flow, the valve 55 elements of said check valves having interengaging parts by which simultaneous closing of both valve elements is prevented, a pilot cylinder having a piston reciprocating therein and connected to the valve element of that check valve which is in the connection to said pull-back ram, connections for admitting a fluid under pressure 60 selectively to opposite sides of said piston for causing movement of said piston in a desired direction, a pump connected to said rams for transferring fluid from one ram to another in either direction selectively, a device for regulating the delivery of said pump in order to change the delivery from one ram to the other, an operating cylinder having a reciprocating piston 65 70 75

- therein connected to said regulating device for operating the latter, connections to said operating cylinder on opposite sides of its piston for causing selected actuation of that piston, a controlling device to which the connections from said operating cylinder and said pilot cylinder lead, whereby the pistons in both of these cylinders will be operated concomitantly in a direction determined by said control device, manually operated means for operating said control device to admit fluid to said pilot and operating cylinders in a manner to cause a downward movement to said platen, and means responsive to the pressure in said main ram for operating said control device in a manner to cause a return movement of said platen after the pressure in said main ram has reached a selected pressure.
22. In a hydraulic press system, a platen, a main ram and a pull-back ram connected to said platen for operating it in alternate directions, a source of fluid under pressure, a connection from said source to each of said rams, a separate check valve in the connection to each ram and having a movable valve element opening for flow from said source to the ram and automatically closing to prevent reverse flow, the valve elements of said check valves having interengaging parts by which simultaneous closing of both valve elements is prevented, a pilot cylinder having a piston reciprocating therein and connected to the valve element of that check valve which is in the connection to said pull-back ram, connections for admitting a fluid under pressure selectively to opposite sides of said piston for causing movement of said piston in a desired direction, a pump connected to said rams for transferring fluid from one ram to another in either direction selectively, a device for regulating the delivery of said pump in order to change the delivery from one ram to the other, an operating cylinder having a reciprocating piston therein connected to said regulating device for operating the latter, connections to said operating cylinder on opposite sides of its piston for causing selected actuation of that piston, a controlling device to which the connections from said operating cylinder and said pilot cylinder lead, whereby the pistons in both of these cylinders will be operated concomitantly in a direction determined by said control device, manually operated means for operating said control device to admit fluid to said pilot and operating cylinders in a manner to cause a downward movement to said platen, and means responsive to the pressure in said main ram and operable on said control device to cause a return movement of said platen, a pre-determined and adjustable time interval after the pressure in said main ram has reached a selected pressure.
23. In a hydraulic press system, a platen, a main ram and a pull-back ram connected to said platen for operating it in alternate directions, means for delivering a fluid under pressure to said rams selectively to operate them in alternate directions, additional fluid actuated means operable for changing said delivering means and causing a change in the ram to which fluid is delivered, and thus cause operation of said rams selectively in either direction, a master valve controlling admission of fluid to said fluid actuated means, means yieldingly urging said master valve into one operative position in which it causes operation of said pull-back ram, manually controlled means for operating said master valve

against said urging means into a different position in which it causes actuation of said main ram, a latch for releasably securing said master valve in said last named position, and means responsive to the pressure in said main ram and operable upon said latch to release said master valve element when the pressure in said main ram reaches a pre-determined pressure. 5

24. In a hydraulic press system, a platen, a main ram and a pull-back ram connected to said platen for operating it in alternate directions, means for delivering a fluid under pressure to said rams selectively to operate them in alternate directions, fluid actuated means for determining the operation of said fluid delivery means to 10 cause selected operation of said rams, a master valve controlling admission of fluid to said fluid actuated means, means yieldingly urging said master valve into one operative position in which it causes operation of said pull-back ram, manually controlled means for operating said master valve against said urging means into a different position in which it causes actuation of said main ram, a latch for releasably securing said master valve in said last named position, means responsive to the pressure in said main ram and operable upon said latch to release said master valve element when the pressure in said main ram reaches a pre-determined pressure, and means for retarding the operation of said last named 20 means upon said latch for a selected interval of time after said pre-determined pressure has been reached. 25

25. In a hydraulic motor, an operated member, a main ram and a pull-back ram connected to said member for operating it in alternate directions, a source of fluid under pressure, means including a pump and selectively operable for transferring fluid between said rams alternately, a passage connecting said source and each ram, a valve in each passage, means cooperating with said valves to prevent simultaneous closing of both valves, the valve in the passage to the main ram being a free check valve and normally closing to prevent fluid flow from said main ram toward said source, means for reversing the delivery of said transferring means from one ram to the other, fluid pressure operated means outside of said passages and connected to and operating the valve in the passage to the pull-back ram in both directions selectively, fluid pressure operated means connected to and operating said reversing means, and means for controlling the flow of operating fluid under pressure to both of said pressure operated means. 40 45

26. In a hydraulic motor, an operated member, a main ram and a pull-back ram connected to said member for operating it in alternate directions, a source of fluid under pressure, means including a pump connected to said rams and selectively operable for transferring fluid between said rams alternately and cause operations of said member, valve means in the connection from said transferring means to said pull-back ram operable for preventing flow therethrough in a direction from said pull-back ram towards said transferring means, a conduit connecting said source to said connection having the valve means, at a point between said transferring means and said valve means, a valve in said conduit operable to prevent flow therethrough in a direction from the pump toward said source, and to pass fluid in the opposite direction, and means operable by said member during an operation of said member by said pull-back ram, for passing fluid from said 50 55 60 65 70 75 80 85 90 95 98 99 100

transferring means, at the conduit connected side, to said source, to stop said member and hold it in stopped position while said transferring means continues to deliver fluid towards said 5 pull-back ram.

27. In a hydraulic motor, an operated member, a main ram and a pull-back ram connected to said member for operating it in alternate directions, a source of fluid under pressure, means including a pump connected to said rams and selectively operable for transferring fluid between said rams alternately and cause operations of said member, valve means in the connection from said transferring means to said pull-back ram 10 operable for preventing flow therethrough in a direction from said pull-back ram toward said transferring means, a conduit connecting said source to said connection having the valve means, 15 at a point between said transferring means and said valve means, a valve in said conduit operable to prevent flow therethrough in a direction from the pump toward said source, and to pass fluid in the opposite direction, means operable by said member during an operation of said member by said pull-back ram, for passing fluid from said transferring means, at the conduit connected side, to said source, to stop said member and hold it in stopped position while said transferring means continues to deliver fluid toward said pull-back ram, pipe means connecting said source to each of said rams, a valve in the pipe means leading to the main ram, a valve in the pipe means leading to the pull-back ram, and means for preventing simultaneous closing of both valves in said pipe means. 5 10 15
